UNITED STATES PATENT OFFICE.

JOHN T. KELLY, OF NEW YORK, N. Y., ASSIGNOR OF ONE-HALF TO GEORGE M. JONES, OF PITTSBURG, PENNSYLVANIA.

DESIGN FOR A COUPLING MEMBER FOR RADIATOR-VALVES.

SPECIFICATION forming part of Design No. 33,259, dated September 25, 1900.

Application filed March 28, 1900. Serial No. 10,559. Term of patent 14 years.

To all whom it may concern:

Be it known that I, JOHN T. KELLY, a resident of New York, (Brooklyn,) in the county of Kings and State of New York, have invented and produced a new and useful Design for a Coupling Member for Radiator-Valves; and I do hereby declare the following to be a full, clear, and exact description thereof.

My design relates to a coupling member for radiator-valves, the essential characteristic of which is the rectangular box-like form of the body, having one side thereof rounded off.

In the accompanying drawings, illustrating my design, Figure 1 is a perspective view of the coupling member, and Fig. 2 is a side view of the same.

The coupling member 1 consists, essentially, of a rectangular box, having one corner rounded off, as shown at 2, to form a curved side and having a threaded opening

3 in the rectangular face 4 opposite the curved side, thereby giving such coupling member the appearance of a very short elbow, square in cross-section. The member is provided with the circular projecting flange 5 and the projecting cone 6, surrounding the opening 7 in the top thereof. The corners of the rectangular face 4 are cut away, as indicated at 8. The rectangular form of the body, having one corner rounded off to form a curved side, gives to the coupling member a unique and pleasing appearance.

What I claim is—

The design for a coupling member for radiator-valves herein shown and described.

In testimony whereof I, the said JOHN T. KELLY, have hereunto set my hand.

JNO. T. KELLY.
